UNITED STATES PATENT OFFICE.

HENRY WALCH, OF HOBOKEN, NEW JERSEY.

DESIGN FOR A BASE-PLATE FOR BASE-BALL-SCORE CARDS.

SPECIFICATION forming part of Design No. 25,587, dated June 2, 1896.

Application filed April 3, 1896. Serial No. 586,128. Term of patent 7 years.

To all whom it may concern:

Be it known that I, HENRY WALCH, a citizen of the United States, residing at Hoboken, Hudson county, New Jersey, have invented 5 and produced a new and original Design for Base-Plates for Base-Ball-Score Cards, of which the following is a specification, reference being had to the accompanying drawing, which shows a face view of my newly-de-10 signed base-ball-score card.

The leading feature of my design consists of a base-plate for base-ball-score cards containing the representation of two pairs of concentric circles, a pitcher and catcher between 15 one pair of circles, a standing and sitting ball-player between the other pair of circles, and a central ball, bats, and a bow.

a b and a' b' represent two pair of concentric circles. Between the circles a b are represented a pitcher c and a catcher d, while 20 between the circles a' b' are represented a standing ball-player e and a sitting ball-player f. Centrally there are represented upon the base-plate a ball g, bats h, and a bow i. 25

What I claim is—

The design for a base-plate for base-ball-score cards, substantially as herein shown and described.

HENRY WALCH.
